UNITED STATES PATENT OFFICE

FREDERICK L. RE QUA, OF SAN FRANCISCO, AND ARION S. KALENBORN, OF REDWOOD CITY, CALIFORNIA, ASSIGNOR TO WELDING SERVICE INC., OF SAN FRANCISCO, CALIFORNIA, A CORPORATION OF CALIFORNIA

RAIL-GRINDING MACHINE

Application filed November 15, 1926. Serial No. 148,449.

This invention relates generally to machines for surfacing or grinding rails of railway tracks.

The electrical arc method of welding rails has now come into general use on both electrical and steam railroads. An electrical weld however leaves a roughened surface, thus necessitating the use of suitable apparatus for resurfacing the rails. For this purpose it has been proposed to employ a portable grinding machine mounted upon a truck. These machines generally comprise a single grinding wheel adjustably mounted upon the truck and driven by an electric motor through a universal connection. Such machines have not been satisfactory because of the inadequacy of the grinding wheel adjustments and because the use of a single grinding wheel necessitates bodily turning the truck around before the other rail can be ground. Furthermore, the drive connection between the motor and wheel make such machines complicated and expensive to manufacture.

It is an object of this invention to devise a rail grinding machine which need not be removed from the track to grind both rails.

It is a further object of this invention to generally improve upon the adjustments for controlling the grinding wheel of a rail grinding machine, thereby increasing its operating efficiency.

It is another object of this invention to devise a novel form of drive for the grinding wheels of a rail surfacing machine which will incorporate a motor having a grinding wheel mounted directly upon each end of its shaft.

Further objects of this invention will appear from the following description in which we have set forth the preferred embodiment of our invention. It is to be understood that the invention is to be accorded a range of mechanical and electrical equivalents consistent with the state of the prior art.

Referring to the drawings:

Figure 1 is a plan view of a rail grinding machine incorporating the principles of this invention.

Fig. 2 is a transverse cross sectional view taken along the line 2—2 of Fig. 1.

Fig. 3 is a detail showing the construction of the locking mechanism for the shiftable motor carriage. 55

The invention comprises generally a wheeled frame or truck which is adapted to support a grinder motor in such a manner that the motor may be shifted bodily transversely of the frame. The motor is provided with a double ended shaft and a grinder wheel is directly mounted upon each end so that by shifting the motor one wheel may be made to operate upon one rail and upon shifting the motor in a different position, the other wheel may be operated upon the other rail. The mounting for the motor upon the wheeled frame comprises a transversely shiftable carriage, to the lower side of which the motor is secured. The motor is also bodily adjustable in a vertical direction by providing an adjustable mounting for the motor upon the shiftable carriage. This latter adjustment is preferably provided with a manual control designated so that the position of the grinding wheels with respect to the rails of a track may be adjusted from either side of the machine. To facilitate accurate positioning of the grinder wheels the shiftable carriage is preferably mounted upon rollers so as to move with substantially no friction. 80

A lock-95

ing device is provided for fixing the carriage with respect to the frame when it is desired to remove the machine from the track.

The specific embodiment of the invention which we have illustrated in the drawing comprises a frame 10 supported by means of wheels 11, the wheels being adapted to fit that gauge of track with which the machine is intended to operate. The frame has been shown as consisting of a pair of end members 12 connected together at their ends by a pair of arched side members 13. The end members 12 may be tubular axles extending between the wheels 11. Shiftably disposed upon the end members 12 there is a carriage designated generally as 14, to the under side of which is mounted a grinder motor 15. This motor is preferably electrical although to suit varying conditions we may employ a motor of the internal combustion type or motors operating from steam or compressed air. The particular form of carriage which we have illustrated comprises a pair of longitudinal members 17 interconnected by a pair of transverse brace members 18.

The ends of the longitudinal carriage members 17 are adapted to engage and track upon the frame members 12 and are preferably provided with roller bearings to reduce friction to a minimum. Thus referring to Figs. 6 and 7, each end of the longitudinal carriage members 17 is shown as provided with an extension 20 adapted to overlie a frame member 12. A roller bearing is mounted upon this extension 20, the bearing in this instance comprising a roller shell 21 positioned upon the axle 22, rollers 23 being interposed between the shell 21 and the axle. The inner side of the frame members 12 are also engaged by rollers, the roller assemblies in this instance however being adjustable to permit taking up side play in the carriage. One of these roller assemblies is shown in Fig. 10 and comprises a roller shell 25 disposed upon a suitable shaft 26, rollers 27 being interposed between the shell and shaft. For securing adjustment of the roller, shaft 26 extends eccentrically from one end of a cylindrical block 28, this block being seated within one of the longitudinal carriage members 17. Block 28 may be locked in any desired adjusted position by means of a wedge-shaped locking pin or bolt 29, one end of this bolt being threaded to receive a nut 30 for jamming the bolt into engagement with block 28.

The bottom sides of the frame members 12 are also preferably engaged by rollers mounted upon the transverse carriage members 17. In this instance the rollers are likewise adjustable and, as shown in Fig. 11, comprise a roller shell 32 disposed upon a shaft 33, this shaft extending eccentrically from the cylindrical block 34. Rollers 35 are interposed between the roller shell 32 and the shaft 33.

The cylindrical block 34 is adjustably locked in position by means of locking pin or bolt 36.

For adjustably mounting the motor to the shiftable carriage there is provided a pair of duplicate devices engaging the ends of the motor housing and which in operation are operated simultaneously. Each of these devices preferably comprises a vertically disposed screw 38 threaded within a nut 39 which is seated in one of the longitudinal carriage members 17. Upon the lower end of the screw 38 suitable means is provided for attachment to the motor housing. For example, there is shown a V-block 40 adapted to engage an end portion 41 of the motor housing, this V-block being secured to the screw 38 by means of a suitable thrust bearing assembly 42. The U-shaped bolts 43 serve to clamp the motor housing portion 41 up against the V-block 40. The upper end of the screw 38 is provided with a non-circular portion 44 to which is fixed a hand wheel 46 or other suitable manual control means.

In order to rotate the screws 38 in synchronism and thus maintain the motor shaft horizontal at all times, there is provided a positive drive connection between the two screws. This drive connection has been shown as comprising a pair of sprockets 48 fixed to the screws 38 and about which is entrained the sprocket chain 49. Thus by rotation of either of the hand wheels 46 both screws 38 are rotated to raise or lower the motor relative to the carriage. In order to brace the screws 38 against tension exerted by the sprocket chain 49 there is provided an intermediate bar 50 having its ends suitably journaled upon the screws 38 as by means of the bearing assemblies 51. In order to prevent undue wear of the screws due to accumulation of dirt or grindings from the rails, they are preferably protected by means of extensible guards 52 and 53. The particular form of guards shown are constructed from a plurality of discs 54 of suitable flexible material such as leather, these discs being secured together along their inner and outer edges to form a bellows-like arrangement. To brace the V-blocks 40 against side thrusts from the motor shaft, these blocks are preferably adapted to operate within vertical slides. Thus each of the longitudinal carriage members 17 is provided with a pair of spaced guide members 55 which have tongues 56 adapted to engage within slots 57 provided upon opposite sides of each of the V-blocks 40.

As previously explained, the two grinder wheels are employed and these wheels are mounted directly upon the motor shaft. Thus the motor shaft 60 is extended at both ends and directly secured thereto are the grinder wheels 61. The upper portion of each wheel is preferably inclosed by a suitable guard 62 mounted upon the extended housing portion 41 and carrying a suitable hand hold 63. Be-

cause of the upwardly arched shape of the side frame members 13, there is sufficient space between the wheels 11 to permit free manipulation of the grinder wheels with respect to the rails.

With devices of this kind it is frequently necessary to remove the machine from the track. For this purpose the carriage is provided with a pair of spaced bars 65 extending through lugs 66 provided upon the transverse carriage members 18. In order to lock the carriage with respect to the frame while the machine is being moved, there is provided a pair of locking levers 67 pivotally secured to one of the frame bars 12 as by means of the pivot pin 68. These levers carry fingers 69, which when the levers are turned to the dotted line position shown in Fig. 4, extend adjacent opposite sides of one of the extensions 20. For retaining the levers in either locking or an out-of-the-way position they are longitudinally slidable upon the pin 68 and are provided with inner cam faces 70 engaging the ends of pin 71. Springs 72 serve to urge the levers in a direction to engage the cam faces 70 with the relatively stationary pin 71, these cam faces serving to retain the levers in either one of the two positions.

In operating this machine, after a weld has been made upon one or both of the rails, the machine is arranged so that two of the wheels 11 straddle one of the welded spots. The operator then grasps the nearest hand wheel 46 and the corresponding hand hold 63, and by rotation of the hand wheel raises or lowers the motor shaft until the adjacent grind wheel 61 operates upon the surface of the rail. By rolling the machine along the track the grind wheel may be moved longitudinally of the rails and by shifting the carriage the wheel may be moved transversely of the rails. By manipulation of the hand wheel 46 the sides of the rail may also be ground against the faces of the grinding wheel. When one rail has been finished it is only necessary for the operator to move about to the other side of the machine and then grind the other rail with the other wheel. The freely shiftable carriage and the roller mounting for the same makes possible complete control over movement of the grinding wheel and thus an operator can complete a given number of grinding operations in a minimum of time.

We claim:

1. A rail grinder comprising a wheeled frame adapted to operate upon a railed track, a motor mounted transversely of said frame, said motor having a shaft extending from both ends of the same, a grinding wheel mounted upon each end of said shaft, the distance between the centers of said grinding wheels being substantially different than the gauge of said track, and means for bod-

ily shifting the motor transversely of said frame.

2. A rail grinder comprising a wheeled frame adapted to operate upon a railed track, a motor mounted transversely of said frame, said motor having a shaft extending from both ends of the same, a grinding wheel mounted upon each end of said shaft, means for bodily shifting said motor transversely of said frame, and means for vertically adjusting the position of said motor with respect to said track.

3. A rail grinder comprising a wheeled frame adapted to engage a railed track, a transversely shiftable carriage mounted upon said frame, a motor mounted upon said carriage, means for vertically adjusting the motor with respect to the frame, said motor having a shaft arranged transversely of the frame, and a grinding wheel mounted directly upon said shaft.

4. A rail grinder comprising a wheeled frame adapted to engage a track, a carriage mounted upon said frame and adapted to be shifted transversely of the same, a motor mounted upon the underside of said carriage, said motor having a shaft extending transversely of the frame and extended at both ends of the motor, a grinding wheel mounted directly upon each extended end of the shaft, and means for bodily adjusting the vertical position of the motor while maintaining the transverse relationship of the shaft.

5. A rail grinder comprising a wheeled frame adapted to engage a track, a carriage mounted upon said frame and adapted to be shifted transversely of the same, a motor mounted upon the underside of said carriage, said motor having a shaft extending transversely of the frame and extended at both ends of the motor, a grinding wheel mounted directly upon each extended end of the shaft, and means including a dual manual control operable from either side of the vehicle for bodily adjusting the vertical position of the motor.

6. A rail grinder comprising a wheeled frame, a carriage mounted upon said frame, said carriage being shiftable transversely of the frame, a motor having a shaft extending from both ends of the same, a grinding wheel mounted directly upon each extension of the shaft, a separate adjustable mounting for securing each end of the motor to the underside of the carriage, and means for effecting simultaneous adjustment of said mountings.

7. A rail grinder comprising a wheeled frame, a carriage mounted upon said frame, said carriage being shiftable transversely of the frame, a motor having a shaft extending from both ends of the same, a grinding wheel mounted directly upon each extension of the shaft, a separate adjustable mounting for securing each end of the motor to the underside of the carriage, a separate manual con-

trol for each mounting, and means for effecting simultaneous adjustment of the mounting upon actuating either one of the controls.

- 5 8. A rail grinder comprising a wheeled frame, a transverse track horizontally mounted on said frame, a carriage operably disposed on said track and freely shiftable by directly applied manual force, a motor 10 mounted on said carriage and having a horizontal shaft, a grind wheel mounted directly upon each end of said shaft, the distance between the centers of said wheels being substantially different from the gauge of said 15 wheeled frame, and means for operably adjusting the motor and grind wheels in a vertical direction relative to the rails of a track to be ground.

9. A rail grinder comprising a wheeled 20 frame adapted to operate upon a railed track, a transversely shiftable carriage mounted upon said frame, means engageable by an operator from either side of said frame for shifting said carriage, a motor carried by 25 said carriage, a pair of grind wheels carried by said carriage, said grind wheels being arranged one adjacent each side of the carriage, means forming a driving connection between said motor and both said grind wheels, said 30 grind wheels being shiftable laterally of the frame with said carriage, and means for vertically adjusting each grind wheel with respect to the track.

10. A rail grinder comprising a wheeled 35 frame adapted to operate upon a railed track, a horizontal transverse drive shaft, a transversely shiftable carriage supporting said drive shaft upon said frame, means for effecting vertical adjustment of said shaft, 40 said means serving to retain said shaft in substantially horizontal position, a grind wheel mounted upon each end of said shaft, one grind wheel serving to effect grinding operation upon one side of the machine and 45 the other grind wheel serving to effect grinding operations upon the other side of the machine, and motive means for driving said shaft.

11. A rail grinder comprising a wheeled 50 frame adapted to operate upon a railed track, a carriage mounted upon said frame, said carriage being freely shiftable transversely of the frame responsive to direct manual thrust applied to the carriage, a pair of grind 55 wheels supported by said carriage adjacent either side of the same, and means for effecting vertical adjustment of said grind wheels, said means including a pair of manual control members carried by said carriage 60 and adjacent either side of the same, whereby an operator can laterally and vertically adjust a grind wheel by actuating one of said control members.

12. A rail grinder comprising a wheeled 65 frame adapted to operate upon a railed

track, a motor supported by said frame, a pair of grind wheels carried by and located adjacent either side of said frame, means for connecting both said grind wheels to said motor, means for simultaneously shifting both said grind wheels laterally of said track, and means for vertically adjusting each grind wheel with respect to the track.

In testimony whereof, we have hereunto set our hands.

FREDERICK L. RE QUA.
ARION S. KALENBORN.
